UNITED STATES PATENT OFFICE

155,301

DESIGN FOR A TRANSPOSITION BRACKET

Clyde J. Lowrey, Dayton, Ohio, assignor of one-half to John C. Weigel, Dayton, Ohio

Application January 30, 1948, Serial No. 144,149

Term of patent 14 years

(Cl. D26—9)

To all whom it may concern:

Be it known that I, Clyde J. Lowrey, a citizen of the United States, and a resident of Dayton, in the county of Montgomery and State of Ohio, have invented a new, original, and ornamental Design for a Transposition Bracket, of which the following is the specification, reference being had to the accompanying drawings, forming part thereof, in which:

Figure 1 is a perspective view of the transposition bracket, showing my new design;

Figure 2 is a side elevational view;

Figure 3 is a top plan view;

Figure 4 is a bottom plan view;

Figure 5 is an end elevational view; and

Figure 6 is a vertical cross-sectional view taken along line 6—6 of Figure 2.

The characteristic features of my design reside in the portions shown by means of full lines in the drawing.

I claim:

The ornamental design for a transposition bracket, substantially as shown and described.

CLYDE J. LOWREY.
